MATTRESS TUFTING MACHINE

Joseph W. Droll, Chicago, and Alex H. Olson, Evanston, Ill., assignors to Droll Patents Corporation, Chicago, Ill., a corporation of Delaware

Application April 20, 1935, Serial No. 17,428

24 Claims. (Cl. 45—138)

The invention relates to mattress tufting machines.

One object of the invention is to provide an improved mattress tufting machine which comprises compressors with members for compacting the mattress substantially at all points where the tufts are to be applied and in which the compressors are counterbalanced in their vertical movement so they may be easily shifted by manual force in their operation to receive and compress a mattress.

Another object of the invention is to provide a mattress tufting machine which comprises compressors which are mounted for conjoint pivotal movement so the mattress can be swung into vertical position for convenience in the insertion of the tufts, in which the compressors are substantially counterbalanced in their vertical movement while they are locked against swinging movement, so they can be easily operated to receive and compress a mattress by manual force.

Another object of the invention is to provide a mattress tufting machine in which the compressors are mounted for relative vertical and conjoint pivotal movement, in which the compressors are provided with trunnions extending into the supporting standards which are adapted to move into coaxial or interfitting relation so the compressors will be substantially counterbalanced for pivotal movement.

Another object of the invention is to provide a mattress tufting machine which comprises compressors which are adapted to be separated and brought together for receiving and compressing the mattress and are pivotally movable when the mattress is compressed so the mattress can be positioned vertically for the insertion of the tufts and in which the compressors are locked against rotation when they are separated and automatically unlocked for conjoint pivotal movement when the compressors have been brought together into compressing position.

Another object of the invention is to provide a mattress tufting machine having a compressor for the lines of tufts with screw-means for simultaneously and equidistantly adjusting the members to vary the spacing between the tufts.

Other objects of the invention will appear from the detailed description.

The invention consists in the several novel features which are hereinafter set forth and more particularly defined by claims at the conclusion hereof.

In the drawings:

Fig. 1 is an end elevation of a machine em-

bodying the invention, the compressors being shown separated in position to receive, or for the removal of, a mattress. Fig. 2 is a similar view showing the compressors with a compressed mattress and swung into vertical position for tufting. Fig. 3 is a plan. Fig. 4 is a transverse section taken on line 4—4 of Fig. 3. Fig. 5 is a vertical longitudinal section through one end of the machine on line 5—5 of Fig. 4. Fig. 6 is a perspective showing the slidable connection between one end of the compressors and the trunnions on the compressors respectively. Fig. 7 is a detail of the trunnions on the compressors in one of the standards of the supporting structure. Fig. 8 is a perspective showing the trunnions on the compressors in the position assumed when the compressors are together in compressing position and are free for conjoint swinging movement. Figs. 9 and 10 are sections on line 10—10 of Fig. 3, respectively, showing the screw-means for adjusting the lower and upper compressor members to vary the spacing of the tufts.

The invention is exemplified in a machine comprising a pair of standards 14 at the ends of the machine, which are rigidly connected together adjacent their lower ends by a channel-bar 15, and are supported on bases 13 for vertical movement, as hereinafter described, a lower compressor pivotally supported in and vertically movable with the standards, and an upper compressor 30 which is vertically sidable relatively to the lower compressor and in the standards.

The lower compressor comprises a suitable rectangular frame 16, pairs of longitudinally extending bars 20 which are supported by the frame 16 and transversely adjustable thereon, as hereinafter described, and a series of upwardly tapered compressor members 17, each provided with a longitudinal slot 18 and enlarged openings 19 at the points where the tufts are to be applied to the mattress and fixed to one pair of bars 20. Each compressor-member 17 extends longitudinally to compress the mattress for a complete longitudinal line of tufts and the side bars 20 of each compressor are slidably held on the frame 16 by a bar 21.

The lower compressor is supported at either end for vertical movement with the standards 14 and for pivotal movement therein by a trunnion 30 which fits in cylindrical bearing 31 in one of the standards 14; a block or bracket 26 integral with trunnion 30; a suspension bar 23 which is fixedly secured by a screw 27 to block 26; a block 25 to which the bar 23 is adjustably secured by a pin 24 and a series of holes 24a, and which is 55

fixedly secured to a plate 22 on an end of the lower compressor-frame 16. Bar 23 is confined in a channel 28 in block 26 and held therein by a cap-plate 29. A plate 32 is secured to the end of each trunnion 30 to hold the frame 16 against endwise movement in standards 14.

The upper compressor comprises a rigid rectangular frame 33, a series of compressor-members 34 complementary to the members 17 on the lower compressor, each for compressing the mattress for a complete longitudinal line of tufts and pairs of bars 35 which are carried by, and transversely movable on transverse underlying bars 36 which are fixed to frame 33. The upper compressor has fixedly secured to each of its ends, a block 42 and a plate 41. The upper compressor 33 is adjustably connected at either end by a pin 40 and a series of holes 40^a to a bar 37, the upper end of which is fitted in a channel in block 20 42. A trunnion-block 39 is fixedly secured by a screw 43 to each bar 37 which moves vertically with the upper compressor and each block 39 is provided with a vertically elongated laterally projecting stud 45, which slides vertically in a slot 25 46 in the standard 14. Bar 23, which is fixed to move with the lower compressor and its trunnion block 26, is slidably fitted in a channel 48 in block 39 and in a channel in block 42, both of which blocks move with the upper compressor. Bar 37, 30 which moves vertically with the upper compressor, is slidably fitted in a channel 49 in the lower trunnion-block 26 and in a channel in the block 25 which is fixed to the lower compressor. Cap-plate 44 holds the bar 23 in channel 48, and cap-plate 29 holds bar 37 in channel 49. These bars and sliding connections with the aforesaid blocks connect the upper and lower compressors for relative rectilinear movement in their separation to receive a mattress and while they are being brought together to compress the mattress. The vertical movement of the upper compressor relatively to the standards 14 and the lower compressor is effected by a pair of links or pitmans 58, the upper ends of which are pivotally connected to trunnions 60 which project laterally from the blocks 39 and the studs 45, which move with the upper compressor.

When the compressors are separated, the elongated studs 45 which travel in vertical slots 46 in the standards 14 prevent pivotal movement of blocks 39 and, through bars 23, 37 and block 26, prevent pivotal movement of the lower compressor in the cylindrical bearings 31 for the cylindrical studs 30. When the upper compressor is lowered, the studs 45 pass out of slots 46 and into recesses or open-ended slots 47 which are provided in the trunnions 30 and plates 32, so that the trunnions 60 on the upper compressor will be coaxial with the trunnions 30 on the lower compressor. This occurs when the compressors have been brought together into mattress-compressing position and automatically releases the compressors for conjoint pivotal movement when the mattress is compressed. As the studs 45 pass out of slots 47 during the lifting of the upper compressor, both compressors become automatically locked against swinging movement.

While the studs 45 on the upper compressor are in interfitting relation with the trunnions 30 on the lower compressor, the operator can swing the compressors with the mattress therebetween into vertical position for convenience in inserting the tufting ties through the mattress. When the compressors are in mattress-compressing position, the trunnions 60 on the upper compressor

are coaxial with the trunnions 30 on the lower compressor, and this permits the trunnions on the upper compressor to rotate in the operating links 58 without displacing them or imparting movement to the operating connections herein-after described. The series of holes 24^a in the plate 22 and block 25 permit the lower compressor to be adjusted on bar 23 for different thicknesses of mattresses, to keep the desired coaxial relation of the studs 60 and 30. The holes 40^a are formed in the plate 41 and bracket 42 for pin 49, so that the upper compressor may be adjusted for the same purpose.

The mechanism for raising and lowering the upper compressor in the standards 14, and relatively to the lower compressor, comprises a hand-wheel 59 which is rotatably mounted in a stud 51 on one of the standards 14; a sprocket-wheel 52 fixed to rotate with hand-wheel 59; a chain 53 operable by sprocket 52; a sprocket-wheel 54 operable by chain 53 and journaled on a stud 55 carried by said standard; a pinion 56 rotatable with sprocket 54; a gear 57 meshing with pinion 56; a shaft 61, which extends longitudinally between standards 14 and is fixed to rotate with gear 57 and provided with enlarged journals 67 in bearings 67^a in the standards 14; a link 58 pivoted at its lower end to a wrist-pin 59 on gear 57 and at its upper end to a stud 60 projecting from one of the blocks 39 to which the upper compressor is fixed for vertical movement through bar 37; and a crank 62 with a wrist-pin 59 to operate a link 58 which has its upper end pivotally connected to the stud 60 on the block 39 for the upper compressor at the opposite end of the machine, so that both ends of the upper compressor member will be simultaneously and equidistantly raised and lowered. Shaft 61 is rotatable through an arc of 180° so that wristpins will be in dead-center positions when the upper compressor is either in its raised or lowered position.

In tufting machines in which the compressors are adapted to compress the mattress for a series of tufts for the entire mattress, the weight of the compressors is such that considerable force is required to lift them and it has been the practice to provide power-means for shifting them to compress and release the mattress. In order to facilitate manual relative shifting of the compressors, the invention contemplates shifting the standards 14 with the lower compressor and the upper compressor in reverse directions so they will be substantially counterbalanced in their relative movements.

For this purpose, the standards 14, with which the lower compressor moves vertically, are each movably sustained by a pair of links 63 at the ends of one of the supporting bases 13, and a pair of levers 64 fulcrumed at 65 to the upper ends of links 63 and pivoted at 66 to one of the standards 14, and a pair of links 68 which are pivoted at 69 to journals 67 which are fixed to the operating shaft 61. Levers 64 are pivoted at 70 to links 68 so that the links will swing the levers on their fulcrs 66. The link-pivots 69 are disposed at diametrically opposite points on journals 67 and so that the links 68 will be in their dead-center positions when the standards 14 are raised and when they are lowered. A stop-arm 73 on the lifting crank 62 for the upper compressor is adapted to engage stops 74 to limit the range of movement of shaft 61, crank 62 and gear 57 to substantially 180°. A stop-arm 71 on gear 57 engages a stop-pin 72 on one of the standards 14 to limit the rotation of said gear and shaft 61

during the lowering movement of the standards.

When the shaft 61 is rotated through hand-wheel 50 and the gearing operated thereby, links 68 will be operated to swing levers 64 to raise or lower the standards 14 relatively to the bases 13, and this occurs simultaneously with the lifting of the upper compressor by the wrist-pins 59 and links 58 which are operated with shaft 61. This exemplifies mechanism for simultaneously lifting the upper compressor and lowering the standards and lower compressor and for simultaneously lifting the standards and lower compressor and lowering the upper compressor. In these movements the load of the upper compressor, while being lowered, is substantially counterbalanced by the lifting of the standards and the lower compressor through the action of lever 64 and links 68. Likewise, the load of the standards and lower compressor in their lowering is substantially counterbalanced by the upper compressor.

The improved mechanism for simultaneously and equidistantly adjusting the members of each compressor comprises a pair of transverse shafts 71, one at each end of each compressor-frame. Each of said shafts is provided with a beveled gear 78 which meshes with a beveled gear 79 on a longitudinal shaft 80 which is adapted to be rotated by a crank 80^a applied to a projecting end thereof to simultaneously rotate both shafts 71. The central compressor member 34 is fixed by a bolt 81 to the compressor-frame so that it is fixed against transverse movement in the frame, because in varying the spacing between the tufts the central line of tufts is always in the center of the frame. The remaining compressor members are slidably transversely on their frame.

A series of screw-sleeves 83 are slidable on and rotatable with each shaft 71, the shafts being square or splined to the sleeves, for this purpose. Each screw-sleeve is threaded to a plate or lug 82 which projects vertically from one of the side-bars of one of the compressor-members, and is connected by means of an annular groove 85 and a plate or lug 84, which is slotted to fit into said groove, to the next adjacent compressor-member. These slot and groove and threaded connections between each screw-sleeve and an adjacent compressor-member and the sliding connection between the sleeve and the screw-sleeve connected to shaft 71 will cause the next compressor-member to slide on the shaft and to correspondingly shift all of the remaining adjustable members with it while the rotation of each screw will equidistantly increase the spacing between all of the members. This exemplifies screw-means for simultaneously and equidistantly adjusting the spacing between compressor-members.

The operation of the machine will be as follows: Assuming the compressors to be separated into position shown in Fig. 1, a mattress will be placed onto the lower compressor and supported horizontally thereby. The operator will then rotate hand-wheel 50 until a half revolution has been imparted to shaft 61 and the compressors are brought together into mattress-compressing position shown in Figs. 4 and 5. This operation of said shaft will operate links 68 to rock levers 64 and lift standards 14 and the lower compressor from the lowered position shown in Fig. 1 to the raised position shown in Fig. 4. Simultaneously, the links or pitman 58 will be operated to lower the upper compressor in the standards. The load of the upwardly moving standards 14 and lower compressor will resist the lowering movement of the upper compressor so the compressors will be

operated in substantial counterbalance to their mattress-compressing position and during such movement the compressors will be self-retained in any position to which they are shifted. As a result of vertically shifting the lower compressor it is lowered to a point where the mattress can be conveniently handled and its axis is raised so the compressor will clear the floor when it is swung into vertical position. The levers 64 are proportioned so the standards will be shifted less than the upper compressor to compensate for the differential in the weight between the standards and lower compressor, and the upper compressor. As the upper compressor reaches its lowered position its studs 45 will slide into slots 47 in trunnions 30 which are journaled in the standards 14 and are attached to the lower compressor. Until the studs 45 enter slots 47 the upper compressor will be locked against rotation and the lower compressor, by slidable connecting bars 23, 27 between the compressors, will also be locked against rotation. When the studs 45 are seated in the trunnions 30, the trunnions 60 on the upper compressor will be coaxial with the trunnions 30 of the lower compressor and both compressors will be free and locked together so they can be conveniently swung into vertical position to bring the mattress into vertical position for the insertion of the tufts.

The compressors can be rotated without displacing the operating links 58 for the upper compressor because the trunnions 30 and 60 are then coaxial. When the mattress has been tufted, the compressors are again rotated to a horizontal position to bring the studs 45 in registry with the lower end of slots 46 in standards 14. The operator will then reversely rotate the hand-wheel 50 to impart a reverse half revolution to the shaft 61. During this operation, links 58 will lift the upper compressor in and relatively to the standards, the studs 45 sliding in slots 46 serving to lock the compressors against swinging movement. Simultaneously, links 68 and levers 64 will be operated to lower the standards 14. During this operation the load of the rising upper compressor will be substantially counterbalanced by the descending standards 14 and lower compressor. When the upper compressor is in its raised position, the operating links 58 and the standard-lifting links 68 will be in their dead-center positions so the compressors and standards will be self-retained in their assigned positions.

The crank-connections for operating the links 58 pass into dead-center positions both when the upper compressor is raised and when it is lowered, so that they will be self-holding or locking in such positions to retain this compressor in such positions. When the standards are in either raised or lowered position, the links 68 and the crank-pivots 69 on shaft 61 will also be in their dead-center positions, so that this mechanism will be self-locking or self-retained to retain the standards in such positions.

The invention exemplifies a mattress tufting machine in which compressors are provided for compacting the mattress substantially at all points where the tufts are to be applied and are operated so as to be counterbalanced in their vertical movement, and so that they may be easily shifted by manual force; in which the supporting standards which carry the compressors are vertically movable with one of the compressors and the other slidably guided thereby with both compressors pivotally movable for convenience in inserting the tufts; in which the supporting

standards are supported by a system of levers and links and one of the compressors is oppositely movable simultaneously with the movement of the standards; in which the lower compressor is provided with trunnions carried by the standards and the upper compressor is provided with trunnions which are guided by the standards and are adapted to move into coaxial relation with the trunnions on the lower compressor or to interfit therewith for permitting conjoint and balanced pivotal movement of the compressors; and in which the members of each compressor are equidistantly and simultaneously adjustable for different spacings of tufts by means of conjointly rotatable and relatively slidably screw-sleeves operable from a common shaft.

The invention is not to be understood as restricted to the details set forth, since these may be modified within the scope of the appended claims, without departing from the spirit and scope of the invention.

Having thus described the invention, what we claim as new and desire to secure by Letters Patent is:

1. In a mattress tufting machine, the combination of a support, a vertically movable supporting structure carried by the support, an upper compressor guided for vertical movement in the structure, a lower compressor mounted in the structure, and mechanism for shifting the structure vertically and the upper compressor vertically relatively to the structure.

2. In a mattress tufting machine, the combination of a support, a vertically movable supporting structure carried by the support, an upper compressor guided for vertical movement and pivotally movable in the structure, a lower compressor pivotally mounted in the structure, and mechanism for simultaneously shifting the structure vertically and the upper compressor vertically relatively to the structure.

3. In a mattress tufting machine, the combination of a support, a vertically movable supporting structure carried by the support, an upper compressor guided for vertical movement in the structure, a lower compressor mounted in the structure, and mechanism for simultaneously shifting the structure and the upper compressor vertically in opposite directions.

4. In a mattress tufting machine, the combination of a support, a vertically movable supporting structure carried by the support, an upper compressor guided for vertical movement and pivotally movable in the structure, a lower compressor pivotally mounted in the structure, a sliding connection between the compressors, and mechanism for simultaneously shifting the structure vertically and the upper compressor vertically relatively to the structure.

5. In a mattress tufting machine, the combination of a support, a pair of vertically movable supporting standards carried by the support, an upper compressor guided for vertical movement in the standards, a lower compressor mounted in the standards and movable vertically therewith, and mechanism for simultaneously shifting the standards vertically and the upper compressor vertically relatively to the standards.

6. In a mattress tufting machine, the combination of a support, a pair of vertically movable supporting standards carried by the support, an upper compressor guided for vertical movement in the standards, a lower compressor mounted to swing in the standards and movable vertically therewith, and mechanism for simultaneously

shifting the standards vertically and the upper compressor vertically relatively to the standards.

7. In a mattress tufting machine, the combination of a support, a pair of vertically movable supporting standards carried by the support, an upper compressor guided for vertical movement in the standards, a lower compressor mounted to swing in the standards and movable vertically therewith, and mechanism for simultaneously shifting the standards and the upper compressor vertically in opposite directions.

8. In a mattress tufting machine, the combination of a support, a supporting structure carried by the support, upper and lower compressors for a mattress comprising members for compressing a mattress at all points where tufts are to be applied and mounted for conjoint pivotal and relative vertical movements in the structure, connections between the compressors for substantially counterbalancing them for relative vertical movement, and means for operating the compressors.

9. In a mattress tufting machine, the combination of a support, a supporting structure carried by the support, upper and lower compressors for a mattress comprising members for compressing a mattress at all points where tufts are to be applied, mounted for relative vertical and for conjoint pivotal movements in the structure, connections between the compressors for substantially counterbalancing them for relative vertical movement in opposite directions, and means for operating the compressors.

10. In a mattress tufting machine, the combination of a support, a vertically movable supporting structure carried by the support, upper and lower compressors for a mattress comprising members for compressing a mattress at all points where tufts are to be applied, the lower compressor being mounted to move vertically with the structure, the upper compressor being mounted for vertical movement relatively to the structure and the lower compressor, and operating connections for the structure and the upper compressor whereby the compressors will be substantially counterbalanced during relative vertical movement.

11. In a mattress tufting machine, the combination of a supporting base vertically movable supporting standards carried by the base, upper and lower compressors for a mattress comprising members for compressing a mattress at all points where tufts are to be applied, the lower compressor being mounted to move vertically with the standards, the upper compressor being mounted for vertical movement relatively to the standards and the lower compressor and operating means for the standards and the upper compressor comprising means between the compressors whereby they will be substantially counterbalanced during relative vertical movement.

12. In a mattress tufting machine, the combination of a supporting structure, upper and lower compressors carried by the structure, for a mattress comprising members for compressing a mattress at all points where tufts are to be applied, a pivotal connection for the lower compressor carried by the structure, vertically slideable trunnions between the upper compressor and the supporting structure, movable into coaxial position with the pivotal connection for the lower compressor, and means for vertically shifting the upper compressor.

13. In a mattress tufting machine, the combination of a supporting structure, upper and

lower compressors carried by the structure, for a mattress comprising members for compressing a mattress at all points where tufts are to be applied, trunnions for the lower compressor pivotally carried in the structure, vertically slidable trunnions between the upper compressor and the supporting structure, movable into coaxial position with the trunnions for the lower compressor, and means for vertically operating the upper compressor.

14. In a mattress tufting machine, the combination of a supporting structure, upper and lower compressors carried by the structure, for a mattress comprising members for compressing a mattress at all points where tufts are to be applied, a pivotal connection for the lower compressor carried by the structure, slidable trunnions between the upper compressor and the supporting structure, movable into coaxial position with the pivotal connection for the lower compressor, and means for vertically operating the upper compressor comprising a link pivoted to one of the trunnions.

15. In a mattress tufting machine, the combination of a supporting structure, upper and lower compressors carried by the structure, for a mattress comprising members for compressing a mattress at all points where tufts are to be applied, a pivotal connection for the lower compressor carried by the structure, slidable trunnions between the upper compressor and the supporting structure, movable into coaxial position with the pivotal connection of the lower compressor and rotatable in the structure when in such position, and means for vertically operating the upper compressor.

16. In a mattress tufting machine, the combination of a supporting structure, compressors for a mattress, one of which comprises a series of compressor members and means for simultaneously and equidistantly adjusting the members relatively to one another for different spacings of tufts, comprising conjointly rotatable and relatively slidable screws between adjacent members and means for rotating the screws.

17. In a mattress tufting machine, the combination of a supporting structure, compressors for a mattress, one of which comprises a series of compressor members, and means for simultaneously and equidistantly adjusting the members relatively to one another for different spacings of tufts, comprising screw-sleeves, having a threaded connection with one member and a shifting connection with an adjacent member, and a shaft for rotating the sleeves, and on which they are slidable.

18. In a mattress tufting machine, the combination of a supporting structure, compressors for a mattress, one of which comprises a series of compressor members, each for a row of tufts, and means for simultaneously and equidistantly adjusting the members relatively to one another for different spacings of tufts, comprising shafts at the ends of the members, and screws slidable on and rotatable by said shafts and connecting adjacent members.

19. In a mattress tufting machine, the combination of a supporting structure, compressors for a mattress, one of which comprises a series of members for compressing an entire mattress substantially at all places to be tufted and for side and intermediate rows of tufts, and means for simultaneously shifting the members comprising rotatable screw-elements connected to the members respectively, means for conjointly

rotating the elements, and means for axially shifting the elements relatively to one another to maintain the same distance between the members when the spacing is varied.

20. In a mattress tufting machine, the combination of a support, supporting standards carried by the support and connected thereto for vertical movement, an upper compressor slidably connected to and pivoted in the standards, a lower compressor mounted in the standards, mechanism for shifting and supporting the standards vertically and shifting the upper compressor vertically relatively to the standards comprising levers connected to the support and to the standards, a shaft carried by the standards, manually operable gearing for operating the shaft, links connected to the shaft and to the levers for rocking the levers to shift the standards vertically, and crank-operated links connected to the shaft and to the upper compressor for shifting the latter relatively to the standards.

21. In a mattress tufting machine, the combination of a support, standards carried by the support and connected thereto for vertical movement, an upper compressor slidably connected to and pivoted in the standards, a lower compressor mounted in the standards, mechanism for shifting and supporting the standards vertically comprising levers connected to the support and to the standards, a shaft, links operable by the shaft and connected to shift the levers for vertically moving the standards, and means operable by the shaft connected to the upper compressor for shifting the same relative to the standards.

22. In a mattress tufting machine, the combination of a support, upper and lower frames each carrying compressor members, and means for connecting the frames to the support for vertical rotation comprising coaxial trunnions and adjustable connections between the trunnions and each of the frames whereby both of the frames can be adjusted to and from the axis of the trunnions so the upper and lower compressor members will be equidistantly spaced from said axis while the frames are in compressing position for mattresses of different thicknesses.

23. In a mattress tufting machine, the combination of a support, upper and lower frames each carrying compressor members, and means for connecting the frames to the support for vertical rotation comprising coaxial trunnions and slidably adjustable connections between the trunnions and the frames whereby both of the frames can be adjusted to and from the axis of the trunnions so the upper and lower compressor members will be equidistantly spaced from said axis while the frames are in compressing position for mattresses of different thicknesses.

24. In a mattress tufting machine, the combination of a support, upper and lower frames each carrying compressor members, and means for connecting the frames to the support for vertical rotation comprising coaxial trunnions rotatably mounted in the support, blocks on the trunnions and adjustable connections between the blocks and the frames whereby both of the frames can be adjusted to and from the axis of the trunnions so the upper and lower compressor members will be equidistantly spaced from said axis while the frames are in compressing position for mattresses of different thicknesses.
